UNITED STATES PATENT OFFICE.

JAMES E. TARBOX, OF LYNN, MASSACHUSETTS.

REGISTER FOR WHEEL-CARRIAGES.

SPECIFICATION forming part of Letters Patent No. 286,743, dated October 16, 1883.

Application filed February 23, 1883. (No model.)

To all whom it may concern:

Be it known that I, JAMES EDWIN TARBOX, of No. 40 Centre Street, of the city of Lynn, in the county of Essex, of the Commonwealth 5 of Massachusetts, have invented a new and useful Improvement in Registers for Wheel-Carriages, &c.; and I do hereby declare the same to be described in the following specification and represented in the accompanying drawings, of which—

Figure 1 is a transverse section of a register of my invention applied to the seat of a carriage, such register being to indicate the periods of time that the seat may be used by 15 persons or passengers in the vehicle, it being supposed that each person, while remaining in the carriage, will occupy the seat. To every seat to be so used there is to be such a register, and such seat is to be adapted to the vehicle and register in such a manner that the seat, on a person sitting down upon it, shall depress the inking-tablet and cause it to depress the marking-roller spring or arm, so as to force down the marking-roller upon the dial 20 or sheet of paper upon which the registry is to be made. Fig. 2 is a top view of the marking wheel or roller, its screw, and the elastic spring or carrier, and the bearing-wheel thereof.

The nature of my invention is defined in 30 the claims hereinafter presented.

In Fig. 1 of the drawings, A denotes the carriage-seat, which at one of its edges may be supposed to be hinged to the carriage-body and to rest on the upper end of a spindle, B, 35 movable vertically in a platform, C, and provided with a spring, D, for raising it and the seat. To the lower end of this spindle an inking disk or tablet, E, is fixed concentrically with the spindle. The platform C may also 40 be hinged to the carriage-body, so as to be capable, as well as the seat, of being turned upward, such being to enable ink to be smeared upon the lower surface of the inking-tablet as occasion may require. Below the platform C, and at a short distance therefrom and parallel with it, is another platform, F, for supporting the sheet of paper or other material on which the registering-marks are to be made. Instead of using a sheet of paper, 45 the upper surface of the platform may be suit-

ably prepared to receive the markings, and to admit of their being readily removed from it by a sponge or other proper means. The sheet of paper, however, is shown at G as placed on the platform F, there being extended upward 55 through the said platform and sheet an arbor, a, having a spring, b, extending from its lower end, and terminating in a long screw, c, upon which is screwed a marking roller or wheel, d. The spring has adapted to it, as shown, a 60 friction-roller, e, which, when the inking-disk is down, bears against it, the marking-roller then not being in contact with the said disk. On the disk rising upward, the spring will rise with it and cause the marking-roller to bear 65 against the disk, or the circular part thereof, on which the ink may be laid. The arbor a is that of the hour-hand of a time-piece movement, (shown at H.) Instead of the arbor being caused to revolve but once in twelve hours, 70 I prefer to have the time-piece movement constructed to cause the arbor to revolve but once in six hours. As the arbor revolves, it will carry the spring b, its screw c, and the marking-wheel d around with it, and as the wheel, 75 when a passenger or person sitting upon the seat, will be borne down upon the platform or paper, such wheel will be caused to revolve and traverse in a helical path, and in so doing will mark the platform or paper. The arcal extent of the mark made will indicate the time the wheel may have been performing the task or the person has occupied the seat. While the seat may not be occupied and the mainspring of the time-piece movement may be wound 80 up, the spring b, with the roller d, will continue to revolve; but the roller will be off the paper and against the inking-disk, and by rolling against it will be freshly supplied with ink. 85

From the above it will be seen that while the seat may be occupied by a passenger or person sitting upon it, the inking-roller will be marking the paper; but on his rising from the seat the marking of the paper will cease, 90 and will not again take place until the seat may be again occupied by a sitter.

It will be evident that without the seat the apparatus may be used to register or indicate the times when a watchman may visit a room 95 100

in a building or mill during the night, he being obliged at each visit to press the spindle down, so as to cause the marking-roller to touch or move against the paper. By reason of the 5 roller, while traveling on the platform or paper, revolving on a screw, the orbit of revolution of such roller will be a helix, and consequently the marks made by the roller will not override each other.

10 I claim—

1. The register, substantially as described, consisting of the time-piece movement, the elastic arm or spring, its screw and marking-roller, the dial or paper-sustaining platform, the ink-15 ing-disk and its operative spindle, and spring,

all being adapted in manner and to operate essentially as set forth.

2. The combination of a movable seat with a register, substantially as set forth, consisting of a time-piece movement, an elastic arm or spring, its screw and marking-roller, the paper-supporting platform, a marking-disk and its operative spindle, and spring, such seat resting on the spindle, and all being adapted and to operate essentially as explained.

JAMES EDWIN TARBOX.
